UNITED STATES PATENT OFFICE.

BENEDICKT SCRIVANI, OF CAMDEN, NEW JERSEY.

HARMONY-BOX FOR TALKING-MACHINES.

1,373,677.

Specification of Letters Patent.

Patented Apr. 5, 1921.

Application filed April 17, 1920. Serial No. 274,572.

To all whom it may concern:

Be it known that I, BENEDICKT SCRIVANI, (a former subject of Italy, who has declared his intention of becoming a citizen of the 5 United States,) residing at Camden, in the county of Camden and State of New Jersey, have invented new and useful Improvements in Harmony-Boxes for Talking-Machines, of which the following is a specification.

10 My invention relates to new and useful improvements in harmony boxes for talking machines, and has for its object to provide an exceedingly simple and effective device of this description of compact and 15 durable construction, particularly adapted for use in talking machines and which will obviate hollow and other objectionable effects while increasing the sonority, mellow-ness and other good qualities in sounds.

20 Another object of the invention is to provide a duplex amplifier having sounding board tongues therein, arcuate in longitudinal cross section.

A further object of the invention is to 25 provide a longitudinally arcuate sounding board forming one of the inclosing walls of the resonator compartment and to arrange within said compartment a longitudinally arcuate sounding board tongue or interme-30 diate sounding board of less length than the first mentioned sounding board, both of the sounding boards increasing in width toward the outlet end of the harmony box.

A still further object of the invention is 35 to construct a harmony box so that the sound waves emanating from the sound box and tone arm will be divided and conveyed in opposite directions through the duplex amplifier compartments, these divided sound 40 waves being further divided during a portion of their travel through the compartments.

With these ends in view, this invention consists in the details of construction and 45 combination of elements hereinafter set forth and then specifically designated by the claim.

In order that those skilled in the art to 50 which this invention appertains may understand how to make and use the same, I will describe its construction in detail, referring by numerals to the accompanying drawings forming a part of this application, in which:—

Figure 1, is a plan view of my improved 55 harmony box for talking machines, a portion of the top wall being removed to plainly illustrate the interior construction and showing the connection of a tone arm thereto.

Fig. 2, is a longitudinal sectional view 60 thereof with a part of the tone arm shown in elevation.

Fig. 3, is a section at the line 3—3 of Fig. 2.

Fig. 4, is a plan view of a slightly modified form of my invention having a section 65 of the top wall broken away.

Fig. 5, is a longitudinal section thereof 70 with a portion of the tone arm in elevation, and

Fig. 6, is a section at the line 6—6 of Fig. 5.

In carrying out my invention as here embodied, it will be obvious that the harmony box may be attached to the talking machine 75 cabinet in any well known or approved manner, and this harmony box comprises the side walls 2 and 3 the ends of which preferably converge outwardly. These side walls are formed of thin boards, and at the ends 80 of these sides between said sides are located the end walls 4 and 5 which diverge upwardly from their lower ends as plainly shown in Fig. 2. On the top of these sides and ends is placed the top or upper wall 6 85 having an inlet opening 7 midway its length so as to communicate with the two resonator compartments 8 and 9 separated from each other by a vertical partition 10 located between the side walls 2 and 3 and extending 90 the entire height of said side walls said partition bisecting the hole 7 of the harmony box. In each end of the top 6 is formed an outlet opening 11 one of which leads from each compartment 8 and 9, and these 95 openings 11 may be surrounded by a flange 12 secured to the top 6 and projecting upwardly therefrom.

Within each compartment are arranged two vertical or upright flat sounding boards 100 13 and 14 which are connected to the partition 10 the side walls 2 and 3 and the top 6, the inner ends of said flat sounding boards being connected with the partition 10 at 105 points on either side of the inlet opening 7 from which point the pair of sounding boards in one compartment diverge toward their outer ends, said outer ends being con-

nected to the side walls at a point approximately in alinement with the inner edge of the opening 11.

Within each compartment 8 and 9 is also located a sounding board 15 arcuate longitudinally which also acts as the lower inclosing wall, one end of said sounding board being connected to the partition 10 and the other end to one of the end walls while the edges diverge from the partition 10 outwardly to a point approximately midway the length thereof or for a distance equal to the length of the flat sounding boards 13 and 14 from which point the edges of the 15 arcuate sounding board are parallel to each other. Said sounding boards 15 are connected to the flat sounding boards 13 and 14 and to the side walls 2 and 3 along their edges in any suitable manner as by gluing 20 them.

Between the vertical flat sounding boards 13 and 14 is mounted a sounding board tongue 16 which is also longitudinally arcuate and the side edges of which diverge from their inner ends outwardly. The inner end 25 of the sounding board tongue terminates in contact with the top 6 while the outer end or edge is free and terminates in proximity to the inner edge of the outlet opening, but 30 is spaced some distance from said opening. The sounding board tongue is also spaced some distance from the sounding board 15, and has a semi-circular notch 17 formed in its inner end to permit some of the sound 35 waves passing through the harmony box to pass above the sounding board tongue in their travel toward the outlet 11.

The ordinary tone arm 18 is connected with the harmony box in the region of the 40 inlet opening 7 in any well known or approved manner and as the sound box is carried by the tone arm the sound waves emanating in said sound box will be converged through the tone arm 18 to the harmony 45 box, said sound waves will be divided by the partition 10 and enter both of the compartments 8 and 9 and as the sound waves enter 50 said compartments they will be further divided, some passing above the sound board tongue 16 and some below the same in their travel toward the outlets 11.

In Figs. 4, 5, and 6 I have shown a slightly modified form of my invention wherein the side walls are designated by the 55 numerals 2' and 3', the end walls by 4' and 5', and the top by a numeral 6'. Said top has a single inlet opening 7' at one end thereof and an outlet opening 11' at the opposite end, said outlet opening being 60 rounded by a flange 12'.

Within the compartment 8' formed by said side and end walls and top are located the vertical flat sounding boards 13' and 14' one end of each being situated transversely 65 on either side of the inlet opening 7' and

preferably just beyond said opening, and these sounding boards diverge toward their opposite ends or toward the outlet opening 11 as plainly shown in Fig. 4, said sounding boards being attached to the end wall 4, the 70 side walls and the top.

A sounding board 15' longitudinally arcuate is arranged between the flat sounding boards 13 or with their longitudinal edges, which diverge toward the outlet opening 75 are attached to the flat sounding boards, while the ends of said sounding boards 15' are attached to the end walls 4' and 5' said sounding board forming one of the inclosing walls of the resonator compartment 8'. 80

Within this compartment between the flat sounding boards 13' and 14' is located the sounding board tongue 16 longitudinally arcuate and running from a point in the region of the inlet opening 7' to a point adjacent the outlet opening 11' and at the end of this sounding board tongue adjacent the inlet is formed the semi-circular notch 17 forming a passageway from the inlet opening 90 two spaces above said sounding board tongue.

In the same manner as for my preferred form the tone arm 18 is connected with the inlet of the harmony box so that the sound waves passing through said tone arm will 95 enter the resonator compartment and pass through the same both above and below the sound board tongue in their travel to the outlet opening 11.

When in use this harmony box is preferably placed in the motor compartment of a talking machine cabinet with the top wall thereof in line with the top wall of the cabinet being supported by the back sides of said compartment. 100

In actual practice it has been found that a harmony box constructed in accordance with this invention when used in a talking machine is efficient in reducing or practically eliminating sharp, harsh hollow or other 110 unpleasant qualities from the sound transmitted giving a clear, brilliant and mellow quality to the production.

Where the harmony box is to be applied to talking machines during their manufacture the wall here described as the top may be the base board top wall of the motor compartment of the talking machine cabinet with the other parts applied thereto as here described. 115

Of course I do not wish to be limited to the exact details of construction as herein shown as these may be varied within the limits of the appended claim without departing from the spirit of my invention. 120

Having thus fully described my invention, what I claim as new and useful is:—

A harmony box for talking machines, comprising a top having an inlet opening midway its length and provided with an 130

outlet opening at each end thereof, parallel side walls connected with said top, downwardly converging end walls connected with said top and side walls, a partition between 5 the side walls midway the length thereof bisecting the inlet opening and forming two resonating compartments, a pair of flat vertical sounding boards in each compartment connected with the partition, side walls, and 10 top, and diverging from points in the region of the inlet opening on the partition to the side walls at points approximately in aline-

ment with the inner edge of the outlet opening, and a longitudinal arcuate sounding board in each compartment, the ends of 15 which are connected to the partition and one of the end walls, the edges of said sounding board diverging outwardly therethrough, a portion of their length connected to the upright sounding boards and end walls. 20

In testimony whereof, I have hereunto affixed my signature.

BENEDICKT SCRIVANI
